UNITED STATES PATENT OFFICE.

CHARLES L. PAULUS AND ROBERT KAUCH, OF DAYTON, OHIO.

RUDDER BAR FOR AIRCRAFT.

Application filed May 8, 1924. Serial No. 711,882.

To all whom it may concern:

Be it known that we, CHARLES L. PAULUS and ROBERT KAUCH, citizens of the United States, residing at Dayton, in the county of 5 Montgomery and State of Ohio, have invented certain new and useful Improvements in Rudder Bars for Aircraft, of which the following is a specification.

This invention relates to rudder bars for 10 aircraft, and is concerned particularly with improvements in means for locking the bar for the purpose of maintaining a fixed course of flight as when flying cross-country by holding the rudder set against a pressure due 15 to cross winds or the like.

The principal object of the invention is 20 to provide a simplified hydraulic locking means which permits the locking of a rudder bar or the like in finely adjusted positions.

25 The invention as described in the following specifications is illustrated in the accompanying drawing, wherein:

Fig. 1 is a plan view of a rudder bar provided with locking means in accordance with 25 our invention.

Fig. 2 is a central cross section on an enlarged scale taken on the line 2—2 of Fig. 1 through the rudder bar and locking means, showing the latter in elevation.

Fig. 3 is a horizontal sectional detail taken on the line 3—3 of Fig. 2, and

Fig. 4 is a view of the right hand end of the rudder bar.

The rudder bar 10 has the usual connections with the vertical rudder of the airplane and is pivoted at the middle on a post 11 with a housing 12. The post 11 is secured to the floor of the cockpit by the flanged bracket 13. The housing 12 receives a spur gear 14 made rigid with the post 11 by a key 15. The housing 12, being pinned to the bar 10, as at 16, swings therewith on the post 11 about the stationary gear 14. The gear 14 meshes on opposite sides with racks 17 reciprocating in guides 18 in the side walls of the housing 12. The racks 17 constitute the rods of pistons 19 or other element such as a moving vane operating in cylinders 20 in the housing 12. The cylinders 20 are interconnected by a passage 21 which is controlled by a butterfly valve 22 pivoted on a pin 23 bearing in a socket 24 in one wall of the housing 12 and actuated by a rod 25 extending out of the housing 55 through a hollow boss 26 in the opposite wall of the housing 12. The boss 26 is ex-

ternally threaded to receive a packing nut 27 to compress packing about the rod 25 and prevent the leakage of fluid thereby. It will be seen that a swinging movement of the 60 rudder bar transmits reciprocating movement to the pistons 19 so that one is advanced and the other retracted in the cylinders 20.

The cylinders 20 and the passage 21 are 65 filled with a fluid, such as oil, and the reciprocation of the pistons or other element such as a moving vane causes the movement of a solid column of fluid from one cylinder into the other through the passage 21 when 70 the valve 22 is open. It is contemplated to open the valve 22 when an adjustment of the rudder bar is to be made, and to close the valve and thus prevent any further flow of fluid between the cylinders to lock the 75 rudder bar in its adjusted position.

The valve 22 is controlled by a lever 28 fixed on the outer end of the rod 25, and extending toward the rudder bar 10. The free end of the lever 28 is forked as indicated at 29, to receive the edge of an arcuate plate cam 30 fixed on a shaft 31 extending lengthwise of the rudder bar. The shaft 31 is received in bearings 32 at 80 opposite ends of the rudder bar and has 85 affixed thereon a pedal 33 at each end. The pedals 33 are normally horizontal, as shown in dotted lines in Fig. 4, with the valve 22 closed so that the rudder is locked.

In turning either to the right or left, the 90 pilot places his feet on the pedals and in so doing, turns them to the full line position shown in Fig. 4, when the valve 22 is open and pressure applied to the proper end of the rudder bar will swing the bar and 95 change the rudder position. If the pilot wishes to maintain the new line of flight with the rudder deflected, as may be necessary for example, in the case of a cross wind, the valve 22 must be returned to closed position. This is effected by rotating the shaft 31 through the medium of either of the pedals 33 back to the normal position. It is apparent that the present construction enables the operation of the rudder bar free of the locking means and that after the pilot has, for example, brought the plane around a turn and moves the rudder bar into its straight-ahead central position, it is locked in this position automatically 100 when he removes his feet from the pedals, leaving them in the horizontal position.

The deflection of the rudder which is frequently made to offset the torque effect of the propeller may be made by locking the rudder in the proper state of adjustment.

- 5 Troublesome cross winds which otherwise cause a strain on the pilot, as he has to hold the rudder bar against a constant pressure therein, are readily taken care of by locking the rudder bar. It will be appreciated 10 that very close adjustment is possible and the locking can be taken care of in any position of the rudder.

We claim:

1. In combination, a control, a fluid system, a member in said system movable in the movement of said control, and means for controlling the flow of the fluid in said system to lock said member and, with it, said control in adjusted position. 15 2. In combination, a control, a fluid system, a moving vane in said system connected with said control to move therewith, a valve for said system, and means to operate said valve to block said fluid 20 system. 25

3. In combination, a rudder bar, a fluid system, a moving vane in said system connected with said bar to move therewith, a valve to control the flow of fluid in said 30 system, and means on said bar to operate said valve.

4. In combination, a control, a closed fluid system comprising a pair of interconnected chambers, a valve controlling the 35 passage of fluid from one chamber to the other, and a moving vane connected with said control and moving therewith to force fluid from one chamber into the other when the control is moved in one direction and back again when the movement of the control is reversed. 40

5. In combination, a rudder bar, a closed fluid system comprising a pair of interconnected chambers, a valve controlling the 45 passage of fluid from one chamber to the other, a moving vane connected with said rudder bar and moving therewith to force fluid from one chamber into the other when the bar is moved in one direction and back again when the movement of the bar is reversed, and foot operated means to open 50 said valve when movement of said bar is to commence and to close said valve after the adjustment of said bar.

- 55 6. In combination, a rudder bar, means for locking said bar in an adjusted position consisting of a closed fluid system comprising a pair of interconnected chambers, a valve controlling the passage of 60 fluid from one chamber to the other, a vane connected with said rudder bar and moving therewith to force fluid from one chamber into the other when the bar is moved in one direction and back again 65 when the movement of the bar is reversed,

and means on said rudder bar automatically operated when the feet are placed on said bar to open said valve to allow move-

ment of said bar and to close said valve to prevent further movement of said bar when 70 the feet are removed:

7. In combination, a foot-operated bar, a closed fluid system comprising a pair of interconnected chambers, a valve controlling the passage of fluid from one chamber to the other, a vane connected with said bar and moving therewith to force fluid from one chamber into the other when the bar is moved in one direction and back again 75 when the movement of the bar is reversed, and means operable by either foot at either end of the bar for opening and closing said valve. 80

8. In combination, a rudder bar, a closed fluid system comprising a pair of interconnected chambers, a valve controlling the passage of fluid from one chamber to the other, a vane connected with said rudder bar and moving therewith to force fluid from one chamber into the other when the bar is moved in one direction and back again 85 when the movement of the bar is reversed, and means operable by either foot at either end of the rudder bar for opening and closing said valve, comprising interconnected 90 pedals at the ends of said bar, and a shaft connected with said valve movable by either of said pedals. 95

9. In combination, a support, a rudder bar pivoted thereon, a housing movable with said bar, a pair of interconnected fluid cylinders, in said housing, a valve controlling communication between said cylinders, pistons operating in said cylinders, and connections between said pistons and said support to advance one piston in one cylinder and retract the other piston in the other cylinder to force fluid from one cylinder to the other. 100

10. In combination, a support, a rudder bar pivoted thereon, a housing movable with said bar, a pair of interconnected fluid cylinders, in said housing, a valve controlling communication between said cylinders, pistons operating in said cylinders, connections between said pistons and said support to advance one piston in one cylinder and retract the other piston in the other cylinder to force fluid from one cylinder to the other, and a member controlled from 110 said rudder bar for operating said valve. 115

11. The combination as set forth in claim 10, the size of the opening of the communication between the cylinders being proportional in size to the pistons. 125

12. In combination, a support, a cylinder block rotatably attached to said support comprising a pair of interconnected cylinders, a rudder bar rotatably carried by the support and rigidly attached to the cylinder. 130

der block to turn the same in its movements, a pair of pistons in said cylinders, means movable in the movements of said cylinder block with said bar, and a valve controlling the flow of fluid between said cylinders.

13. In an apparatus for maintaining a rudder bar for aircrafts in any desired position, comprising in combination a fixed 10 shaft mounted on the aircraft and rotatably supporting the rudder bar, a fixed sprocket member rigidly attached to the shaft, a casing rotatably attached to the shaft and rigidly attached to the rudder bar and contain-

ing a plurality of slidable members in 15 geared relation to the sprocket member, a plurality of connected oil cylinders and pistons operating therein, carried by the casing, said pistons being actuated by the 20 slidable members upon the movement of the rudder bar, a valve interposed in the passageway between the cylinders normally in a closed position and means for opening said valves.

In testimony whereof we affix our signatures.

CHARLES L. PAULUS.
ROBERT KAUCH.
